COMBINATION ELECTRICAL PICKUP AND
BRIDGE FOR GUITARS AND OTHER IN-
STRUMENTS

William Ernest Harker, Idaho Falls, Idaho

Application February 8, 1946, Serial No. 646,406

1 Claim. (Cl. 84—1.16)

1

This invention relates to a combination electrical pickup and bridge for a guitar or other string instruments and the main object of the invention is to provide a device for picking up the vibrations of the steel strings on a stringed instrument and by use of an amplifier produce a stronger musical tone.

The device can be installed on the musical instrument without damaging or cutting the instrument. It will replace the conventional bridge and it can be removed at any time and replaced by the conventional bridge if an amplifier is not available. The device is retained in place by the pressure of the strings and uses the principle of induction as the strings vibrating in the magnetic field induce alternating current in a coil mounted on the device. These currents are fed to an amplifier which reproduces the vibrations in a speaker in the form of music or sound.

By the use of this device any instrument using steel strings may be made into an electric instrument since only the vibrations of the strings are amplified.

With the above and other objects and advantages in view the invention consists of the novel details of construction, arrangement and combination of parts more fully hereinafter described, claimed and illustrated in the accompanying drawing in which:

Figure 1 is a plan view of an embodiment as applied to a stringed instrument and connected to an amplifier;

Figure 2 is a side view of the device partly in elevation and partly broken away;

Figure 3 is a sectional view on the line 3—3 of Figure 1;

Figure 4 is a sectional view on the line 4—4 of Figure 1 and

Figure 5 is a sectional view on the line 5—5 of Figure 1.

Referring more in detail to the drawing the reference numeral 10 designates a permanent magnet fastened at each end to the pole pieces 12 and 14 respectively by welding 13 or the like.

The pole piece 14 is provided with slots 16 which are relatively spaced to receive the strings 18 of the instrument 20, thus the pole piece 14 functions as a bridge for the instrument. The strings 18 pass over the pole piece 12 but are never in contact with it.

A coil 22 of very fine magnet wire is wound on the magnet 10 and the starting end of the coil is grounded on the pole piece 12 at 24.

The free end of the coil is connected to an amplifier 26 by means of a shielded microphone

2

cord 28 having a plug 30 for insertion into the input of the amplifier. The shield of the cord is also grounded on the device at 32 on the pole piece 14.

5 A cover 34 of insulating material is provided on the coil 34 and serves to protect the cord from damage.

The precise construction of amplifier 26 does not necessarily constitute a part of the invention, 10 since any conventional amplifier may be used when available.

The device can be constructed to be used with an instrument having any number of strings. The length of the permanent magnet can be 15 varied as desired and if the pole piece 14 is lowered it can be used without removing the conventional bridge.

In the device the strings become part of the magnetic path of the permanent magnet, since 20 the bridge poles are made of soft iron and complete the magnetic circuit. The vibration of the strings alternately increase and decrease the magnetic field, thus inducing an alternating or pulsating electro-magnetic piece which can be 25 amplified to reproduce the musical tones of the strings.

The device can be made in any size and shape 30 to fit the instrument with which it is to be used and it does not stop the vibrations of the body of the instrument which gives the instrument its tone.

It is believed that the operation and construction of my device will be apparent to those skilled in the art and it is to be understood that changes 35 in details of construction, arrangement and combination of parts and the size thereof may be resorted to providing they fall within the spirit of the invention and the scope of the appended claim.

40 Having thus described the invention what is claimed as new and desired to be secured by Letters Patent is:

A pickup for use with a stringed musical instrument comprising a permanent bar magnet, 45 pole pieces secured by welding to said magnet at the opposite sides thereof so that said pole pieces will elevate said magnet above said instrument, one of said pole pieces being of a greater height than the other of said pole pieces, the former 50 of said pole pieces having relatively spaced slots in the upper edge thereof to receive the strings of the instrument and serve as a bridge for said strings to maintain said strings in proper relation to said instrument for the playing thereof and to maintain said strings in a plane above

the lower pole piece when said pickup is positioned beneath the strings of said instrument, a coil of fine magnet wire wound on said pole piece, the starting end of said coil being grounded to said lower pole piece, a shielded microphone cord connecting the opposite end of said coil to an amplifier, said cord being grounded to said first pole piece, and a covering of insulating material on said coil for the protection thereof.
